8 Claims. (Cl. 23—230)

This invention relates to burners and finds particular application in the case of burners used for analysis of material in liquid or gas form. The apparatus and procedure of the invention is particularly well suited for the burning and analysis of organic liquids and gases.

Apparatus is known for the determination of sulfur, halogen, and boron content of organic substances by quantitative combustion of the substances. An example of such apparatus is the Dr. Wickbold burner.

These analysis burners are suction burners and comprise four concentrically disposed pipes whereby an inner passageway and three annular passageways are provided. The inner passageway is referred to herein as the first passageway and the innermost annular passageway is referred to as the second passageway, the next annular passageway as the third passageway, and the outermost annular passageway as the fourth passageway. In the known apparatus the oxygen necessary for combustion is passed through the inner or first passageway; the substance to be analyzed is passed through the second passageway; a combustible gas, usually hydrogen, is passed through the third passageway; and excess oxygen is passed through the fourth passageway. The oxygen supply supports combustion, and the hydrogen supply provides a flame to assure burning of the substance to be analyzed (herein referred to as the fuel). In the known apparatus, the exit ends of the pipes terminate in a common plane perpendicular to the axis of the pipes.

These known burners have the disadvantage that the substance to be analyzed burns at the mouth of the respective supply pipes, and solids are deposited at the exit ends of the burner. As a consequence, the pipes, particularly the pipes defining the passageway for the substance to be analyzed or the fuel, may become completely closed so that the device is inoperative, or may become partially closed so that errors occur in the analysis. Moreover, in the known burners, the exit end of the burner is heated to the extent that the substance analyzed, if a liquid, is vaporized within the passageway through which it travels, and, depending on the substance being analyzed, solids are deposited in the pipe by reason of this evaporation in the pipe. This tends to clog the pipe and may occasion errors in analysis.

The thermally stressed parts of the known burners are made up of quartz.

It is a principal object of the invention to provide a burner which is free of the mentioned disadvantages of the known burners.

According to the invention, a burner construction is provided which is characterized in that the burning of the fuel (substance to be analyzed) occurs at a locus spaced from the discharge end of the passageway through which the fuel passes. This prevents the deposit of solids due to burning at the discharge of the fuel supply passageway, and further reduces the extent to which the discharge end of the fuel supply passageway is heated, so that, in the case of liquids, evaporation does not occur or does not occur to as great an extent, as in the case of burners wherein the burning takes place at the discharge of the fuel supply passageway.

According to the invention, a burner comprises a plurality of concentrically disposed pipes providing an

2

inner passageway and separate outer passageways about the inner passageway. Each of said passageways has an inlet end and an outlet end and said inlet ends are disposed adjacent each other and the outlet ends are disposed adjacent each other. Means are provided for introducing fuel into the inlet end of the inner passageway, and means are provided for placing material for facilitating burning (hydrogen and oxygen in the case of the Dr. Wickbold burner) of the fuel into the inlet end of the other passageways.

Further, according to the invention, the fuel and one of the materials for facilitating combustion are admixed at the discharge of the fuel supply passageway (the inner passageway) and additional material for facilitating combustion of the fuel is released from the outer passageway at a point spaced from the discharge end of the two inner passageways.

In accordance with the invention, the burner comprises four concentrically disposed pipes providing a first passageway through the innermost pipe, a second passageway as an annulus about the first passageway, a third passageway as an annulus about said second passageway, and a fourth passageway as an annulus about the third passageway. Fuel is to be introduced into the first passageway and material for facilitating burning of the fuel is introduced through the remaining three passageways.

The invention particularly contemplates an apparatus comprising four concentrically disposed pipes, as just described, and wherein the first, second, and third passageways terminate short of the fourth or outermost passageway. Such construction is provided by terminating the two inner pipes short of the two outer pipes. The two inner pipes can terminate in the same plane which is perpendicular to the axis of the burner and the two outer pipes can terminate in the same plane, also perpendicular to the axis of the burner.

The invention provides the burning procedure wherein at least part of the material for facilitating combustion is conveyed by its delivery pipe to a locus of release spaced from the outlet end of the pipe through which the fuel is conveyed, whereby the material for facilitating combustion is admixed with the fuel at the locus spaced from the outlet end of the fuel delivery pipe, and burning of the fuel occurs at a locus spaced from the outlet end of the fuel delivery pipe. Thus, the fuel is burned at a locus removed from the outlet end of its delivery pipe, and combustion does not start at the said outlet end as is the case for prior art burners. Further, if the fuel is in liquid form, conversion of the fuel into a gas does not take place in the fuel delivery pipe, but rather occurs after discharge of the fuel from the outlet end of its pipe.

In the four pipe burners of the prior art, oxygen is passed through the inner pipe, the fuel is passed through the first annular passageway, hydrogen through the second annular passageway and oxygen through the third annular passageway. According to the invention, fuel is passed through the inner pipe, oxygen can be passed through the first and second annular passageways, and hydrogen can be passed through the third annular passageway. This preferred procedure offers the advantage that the fuel is well shielded from the hydrogen which diffuses readily. The hydrogen provides the igniting flame, maintains the combustion, and assures complete combustion of the fuel. Since the hydrogen is released at a point spaced from the outlet end of the fuel supply pipe, burning tends to occur at a locus spaced from the outlet end of the fuel supply pipe and adjacent the outlet end of the hydrogen supply pipe. Further, this arrangement provides a cooling effect at the burner end of the apparatus.

In another preferred embodiment of the invention, the cross-sectional flow area of the passageways adjacent the

outlet ends thereof, decreases in the direction of the outlet ends. This provides an increase in flow velocity as the fuel and materials for facilitating approach the outlet ends of their respective pipes. Another preferred embodiment, is with respect to the relative cross-sectional flow area of the second passageway (first annular passageway) and the third passageway (second annular passageway). Preferably, particularly where oxygen is passed through the second and third passageways, the cross-sectional flow area of the third passageway is larger than the cross-sectional flow area of the second passageway.

The invention is further described in reference to the accompanying drawing, wherein an elevation view, partially a cross-section, of a device according to the invention is shown.

Referring to the drawing, four pipes 1a, 4a, 5a, and 6a are disposed in concentric relationship and provide an inner or first passageway 1, a second passageway or first annular passageway 4, a third passageway or second annular passageway 5, and a fourth passageway or third annular passageway 6. The pipes terminate in outlet ends indicated by the arrow 14, and the pipes 1a and 4a terminate short of the point of termination of the pipes 5a and 6a, so that the passageways 1, 4 and 5 terminate short of the termination of the passageway 6. The pipe 1a extends rearwardly from the outlet ends 14 and is integral with a connecting link 2 which connects the pipe 1a with a source of fuel or material to be analyzed. The material to be analyzed is contained in the container 3. The pipe 4a extends rearwardly and communicates with the bulb 4b. In similar manner, the pipe 5a extends rearwardly and communicates with the bulb 5b. The bulbs 4b and 5b are communicated respectively with a container 10, by the connecting links 8 and 7. The connecting links 8 and 7 are each outfitted with a valve 9, whereby the flow in the pipes 4a and 5a can be proportioned as is desired. Oxygen can be contained in the container 10. The outer pipe 6a extends rearwardly and connects with a bulb 6b, and this bulb is communicated with a container 13 by a connecting link 11. The connecting link 11 is outfitted with a valve 12. Hydrogen for supporting the combustion can be contained in the container 13.

The cross-sectional flow area of the various passageways, adjacent the outlet ends 14, decreases toward the outlet end. The two inner pipes 1a and 4a converge adjacent the outlet end and provide these pipes as burner nozzles. The cross-sectional flow area of the second passageway (first annular passageway) is smaller than the cross-sectional flow area of the third passageway (second annular passageway). The wall of the pipe 5a, adjacent the outlet ends 14, diverges to provide, on the one hand, the desired reduction of cross-sectional flow area for the third passageway 5 and, on the other hand, the desired cross-sectional flow area for the fourth passageway 6.

The burner can be constructed of quartz, as is known for such burners, and the outer pipe 6a can be a ground section.

The burner operates in a known manner as a suction burner. In use, it can be placed in a fired tube, as is known.

While the invention has been described with reference to

particular embodiments thereof, various modifications will occur to those skilled in the art whose desire it is desired to secure by these letters passed all such modifications as are within the scope of the appended claims.

5 What is claimed is:

1. A burner comprising four concentrically disposed pipes providing a first passageway through the innermost pipe, a second passageway as an annulus about said first passageway, a third passageway as an annulus about said second passageway, and a fourth passageway as an annulus about said third passageway, each of said passageways having an inlet end and an outlet end, and said inlet ends being disposed adjacent each other and said outlet ends being disposed adjacent each other, means for introducing fuel to said first passageway and means for introducing material for facilitating burning of the fuel through the remaining three passageways, said first, second, and third passageways terminating short of said fourth passageway.

10 2. A burner according to claim 1, the cross-sectional flow area of said passageways adjacent the outlet ends thereof, decreasing in the directions of the outlet ends.

15 3. A burner according to claim 1, the cross-sectional flow area of said third passageway adjacent the outlet ends being larger than the cross-sectional flow area of said second passageway adjacent the outlet ends.

20 4. A burner according to claim 2, the cross-sectional flow area of said third passageway adjacent the outlet ends being larger than the cross-sectional flow area of said second passageway adjacent the outlet ends.

25 5. A burner according to claim 1, said pipes being quartz.

30 6. A burner according to claim 1, the two inner pipes terminating in a plane perpendicular to the axis of the burner and the two outer pipes terminating in a plane perpendicular to the axis of the burner.

35 7. The method of burning a fuel which comprises burning the fuel with a burner comprising four concentrically disposed pipes providing a first passageway through the innermost pipe, a second passageway as an annulus about said first passageway, a third passageway as an annulus about said second passageway, and a fourth passageway as an annulus about said third passageway, each of said passageways having an inlet end and an outlet end, and said inlet ends being disposed adjacent each other and said outlet ends being disposed adjacent each other, said first, second, and third passageways terminating short of said fourth passageway whereby three shortened passageways are provided, passing fuel for combustion through said first passageway, passing oxygen through said second and third passageways, and passing a combustible material through said fourth passageway.

40 8. The method of claim 7, wherein the combustion material passed through the fourth passageway is hydrogen.
